[57] CLAIM

The ornamental design for a fabric dialysis-equipment carrier for ambulatory patients, substantially as shown and described.

DESCRIPTION

FIG. 1 is a perspective view of a fabric dialysis-equipment carrier for ambulatory patients showing my new design;

FIG. 2 is a front elevational view thereof;

FIG. 3 is a top plan view thereof;

FIG. 4 is a bottom plan view thereof;

FIG. 5 is a rear elevational view thereof; and

FIG. 6 is a side elevational view thereof, looking toward the left side thereof in FIG. 1.

The cross line shading is intended to represent conventional fabric covering the entire surface of the claimed design.
